UNITED STATES PATENT OFFICE.

WILLIAM KING, OF ST. JAMES, MINNESOTA.

THRASHING-MACHINE.

SPECIFICATION forming part of Letters Patent No. 401,705, dated April 16, 1889.

Application filed July 25, 1888. Serial No. 280,963. (No model.)

To all whom it may concern:

Be it known that I, WILLIAM KING, of St. James, in the county of Watonwan and State of Minnesota, have invented certain new and 5 useful Improvements in Thrashing-Machines, of which the following is a specification, reference being had to the accompanying drawings, and to the letters of reference marked thereon.

10 The object of my invention is to provide a thrashing-machine with devices for separating the grain from the straw, which will be more efficient in operation, and, being simpler, require less power to operate them.

15 My invention consists in the several details of construction and arrangement, hereinafter fully set forth.

In the drawings, Figure 1 is a vertical longitudinal section of a thrashing-machine provided with my improved separator. Fig. 2 is a vertical transverse section, and Figs. 3 and 20 4 are plan views of different parts of the separator.

Similar letters of reference indicate similar 25 parts in the respective figures.

A is the thrashing-machine.

B is the cylinder, and C the concave, the cylinder and concave being provided with thrashing-teeth in the ordinary manner.

30 D is a beater which serves to stop the flying grain when it leaves the cylinder.

The shaker consists of two floors, E' E², and the carrier E, the floor E' being formed of a series of slats, e, secured to two stringers, e'. 35 These slats, as seen in cross-section, are in the form of a right-angled triangle, and arranged just far enough apart to allow the grain, which will slide down their incline faces e², to pass between them, while the short straw and 40 most of the chaff will be carried along on the slats and discharged at the rear end of the machine. The floor E' is horizontal and extends under the concave a short distance, a sufficient space being left between them to 45 enable the shaker to clear the concave when the former is lifted in the operation of shaking. The floor E² is slatted in a manner similar to that of the floor E', and the carrier E consists of a series of longitudinal strips, f, 50 arranged about three inches apart, extending from the slatted floor E² to the straw-discharge

opening in the rear of the machine. These strips f are each provided with pins f', which extend upward and have an inclination toward the rear of the machine. The floor E² is 55 attached to the lower floor, E', as shown, and inclined upward at an angle of about twenty degrees. The strips f are attached to the floor E² and extend rearward at a less degree of inclination. They are suitably braced together laterally and supported at their rear ends by the standards f², secured to the sides of the lower floor, E'.

K K' are rock-shafts, on which are mounted arms K² K³, which support the shaker on each 60 side, and also the grain-tray M. These arms K² K³ are mounted on the shafts about midway of their connections to the shaker and tray, respectively. One of the arms, K², extends downward and is connected by the rod 65 k to the crank L. The tray M has a slight decline toward the rear of the machine, and is provided with a screen, m, at its rear end, through which the grain falls into the hopper 70 W. The other portion of the bottom of the tray is solid.

The operation is as follows: The straw and grain are forced from the concave upon the horizontal part of the shaker and up the inclined floor E² onto the longitudinal slatted carrier. The shaker is given a shaking movement both longitudinally and up and down by the crank movement. The up-and-down movement is important, as it violently tosses the straw and shakes out the grain therefrom. The 80 straw having been carried or thrown up to the longitudinally-slatted carrier E, is caught and tossed up by the pins f, each series throwing the straw to the next series in advance. The grain having been shaken upon the floor E', 85 90 the arrangement of the slats thereof is such that only the grain can pass through to the tray M, the refuse being carried rearward, whence it is discharged. It will be seen that the tray M is also violently shaken coincidently with but reversely of the shaker, and that its movement, together with its inclination, rapidly carries the grain to the hopper W.

The advantages of the construction are apparent, and are dependent upon the peculiar 95 construction of the several parts of the shaker, the movement given thereto, and to the ar-

angement of the shaker, so constructed and operated with a coincidently-moving inclined screen.

I disclaim perforated shakers, as also shaking trays used in connection therewith; but,

Having described my invention, I claim—

In a thrashing-machine, the shaker consisting of the angularly and transversely slatted floors E' E^2 and the longitudinally-slatted carrier E , rigidly mounted thereon, the floor E' being horizontal and the floor E^2 and carrier E inclined, as shown, the shaker E extend-

ing over the floor E' and being provided with rearwardly-inclined pins f' , combined with the shafts K K' , arms K^2 K^3 , mounted on said shafts, a crank, and a connecting-rod, substantially as set forth.

In testimony whereof I have hereunto set my hand and seal.

WILLIAM KING. [L. S.]
